(57) **CLAIM**

We claim the ornamental design for a shoe sanitizer, as shown and described.

DESCRIPTION

FIGS. 1 and 2 are bottom and top isometric views, respectively, of a shoe sanitizer, in which a germicidal light bulb is installed; and,

FIGS. 3, 4, 5, 6 and 7 are, respectively, a top plan view and right-hand side, left-hand side, rear, and front elevation views of the shoe sanitizer shown in FIGS. 1 and 2.

Items shown in broken lines in the drawing figures are for illustrative purposes only and form no part of the claimed design.
